Patented Oct. 3, 1967

208,808

LUBRICATOR FOR LAWN MOWERS AND THE LIKE

Kenneth N. Hasenbank, Minneapolis, Minn., assignor to
Toro Manufacturing Corporation, Minneapolis, Minn.,
a corporation of Minnesota

Filed Apr. 20, 1966, Ser. No. 1,956

Term of patent 14 years

(Cl. D46—1)

FIG. 2.

FIG. 4.

FIG. 1.

FIG. 5.

FIG. 3.

FIG. 1 is a front elevational view of a lubricator for lawn mowers and the like;

FIGS. 2 and 3 are left and right side elevational views respectively;

FIGS. 4 and 5 are top and bottom plan views respectively.

I claim:

The ornamental design for a lubricator for lawn mowers and the like, substantially as shown.
